UNITED STATES PATENT OFFICE.

ERNON V. OLIVER, OF PORTLAND, OREGON.

BOILER FOR STILLS.

Application filed June 4, 1927. Serial No. 198,558.

This invention relates to distilling apparatus and more particularly to a boiler in which water may be converted into steam which is allowed to pass out of the boiler and through a pipe to a suitable condenser.

One object of the invention is to provide a boiler in which the heating chamber is enclosed in a water jacket and the water fed from the water jacket into tubes disposed within the heating chamber so that the water may be quickly heated to a high temperature and converted into steam.

Another object of the invention is to permit products of combustion or an equivalent heating medium to pass upwardly through the heating chamber between and about the water tubes and also provide conduits for the heating medium which extend vertically through the tubes and thereby cause the water tubes to be quickly heated to a very high temperature and maintained at this temperature so that the water will be heated and converted into steam in a very efficient manner.

Another object of the invention is to provide a boiler which will be simple in its construction and consist of a comparatively few number of parts.

Another object of the invention is to arrange the water tubes in banks which are disposed in the heating chamber and securely mounted in communication with the water jacket.

Another object of the invention is to allow a portion of the heating medium to pass upwardly through conduits disposed in the water jacket about the sides of the body and thereby allow the water in the water jacket to be pre-heated before it enters the water tubes in the heating chamber.

Another object of the invention is to cause steam which accumulates in the upper portion of the water jacket to be kept hot and thereby prevented from condensing in the water jacket.

The invention is illustrated in the accompanying drawings, wherein

Figure 1 is a vertical sectional view through the improved boiler;

Fig. 2 is a transverse sectional view through the boiler taken in the line 2-2 of Fig. 1;

Fig. 3 is a vertical sectional view showing a slightly modified form of boiler, and

Fig. 4 is a similar view showing another modified form of boiler.

The improved boiler which is intended to form part of a still includes a body portion 1 which is formed of metal and has a tapered top or upper portion 2 from which extends an outlet neck 3. The body defines a heating chamber which is open at its bottom, as clearly shown in Fig. 1, so that it may be placed over a fire and products of combustion or heated air constituting a heating medium passed upwardly through the body and out through the neck 3 which may constitute a smoke pipe if so desired and have suitable connection with a chimney or the like. It will, of course, be obvious that, if desired, the boiler may be set in place upon an ordinary cooking stove of the coal or gas type. A baffle 4 is mounted in the upper portion of the body and may be adjustable toward and away from the lower end of the neck 3 so that the warm air or products of combustion in the upper portion of the chamber may be directed toward the walls thereof and prevented from passing into the outlet neck too rapidly.

A water jacket 5 is disposed about the body 1 in spaced relation thereto, as shown in Fig. 2, and has its lower end closed by an inwardly extending flange or bottom 6 and its upper portion 7 tapered and terminating in a head or dome 8 which is disposed about the outlet neck or pipe 3 and formed with a side opening in which is fitted a pipe 9 to conduct the steam to a suitable condenser.

From an inspection of Fig. 4, it will be seen that, if desired, pipes 10 may be disposed vertically in the water jacket at opposite sides of the body with their upper and lower end portions bent to extend toward the body. These end portions 11 of the pipes 10

10 are fitted into openings formed in the side walls of the body, and it will be readily seen that the heating medium by passing through the pipes 10 may heat the water in the water jacket before it passes out of the water jacket. A water inlet pipe 12 which may lead from any suitable source of supply is connected with the water jacket as shown in Fig. 1 and provided with a control valve 13 and a water glass 14 is connected with the water jacket in the usual manner so that the amount of water in the boiler may be determined by looking at the water glass and additional water fed into the water jacket when necessary by opening the valve in the supply pipe.

A series of water heating units is disposed

in the chamber defined by the body 1 and each includes an upper tube 15 and a lower tube 16. These tubes extend transversely in the chamber with their open end portions 5 passed through openings in side walls of the body and communicating with the water chamber. Vertically disposed tubes 17 connect the transversely extending upper and lower tubes, and it will be apparent from an 10 inspection of Fig. 1 that water fed into the water jacket will pass through the tubes 16 and up into the tubes 17 until it reaches and enters the upper tubes 15. The normal water level is indicated by a dotted line in Fig. 15 1 and is preferably below the upper walls of the upper tubes as shown so that steam may pass from these tubes into the water jacket and accumulate in the tapered upper portion thereof about the tapered top of 20 the body and about the outlet pipe 3. By this arrangement the hot outlet pipe and upper portion of the body will retain the steam at a high temperature and prevent it from condensing in the upper portion of the water 25 jacket before it has an opportunity to pass out through the pipe 9 to the condenser. If so desired, additional transverse pipes 18 may be disposed in the chamber between the upper and lower pipes, as shown in Fig. 3. 30 It should also be noted that the upper and lower pipes may be staggered, as shown in Fig. 4, so that the heating units may be placed somewhat closer together than shown in Fig. 2 and thereby allow a greater number 35 to be accommodated in the heating chamber while at the same time leaving sufficient space between them for the heating medium to pass upwardly through the chamber. Conductor tubes 19 for the heating medium 40 extend longitudinally through the vertically disposed pipes 17 and have open upper and lower ends which pass through openings formed in the upper and lower walls respectively of the upper and lower tubes 15 and 45 16 and communicate with the upper and lower end portions of the heating chamber. Therefore, the heating medium in addition to passing upwardly about and between the heating units may also pass upwardly 50 through the tubes 19 and constitute internal means for applying heat to water in the heating units. By this arrangement the water in the water tubes will very quickly reach the boiling point when the boiler is in use and the water caused to boil at such a 55 rate that it will be very quickly converted into steam. As previously explained, this steam passes outwardly through the ends of the upper tubes into the water jacket and 60 upwardly through the water jacket into the dome 8 from which it passes through the pipe 9 to a suitable condenser. When necessary, one or more of the heating units may be removed so that it can be repaired or replaced with a new one. 65

Having thus described the invention, I claim:

1. A still comprising a hollow body defining a heating chamber and having its upper end provided with an outlet, a water jacket disposed about said body and having its upper portion provided with a steam outlet, upper and lower water tubes extending transversely through said body and having open ends secured in openings 70 formed in the walls of the body and communicating with said water jacket, water tubes extending vertically between and communicating with said upper and lower tubes, and open-ended conduits for a heating medium extending longitudinally through the vertical water tubes with their end portions extending transversely through the upper and lower water tubes and communicating with the upper and lower portions 75 of said chamber.

2. A still comprising a hollow body defining a heating chamber and having its upper end provided with an outlet, a water jacket disposed about said body and having 80 its upper portion provided with a steam outlet, upper and lower water tubes extending transversely through said body and communicating with said water jacket, water tubes extending vertically between and communicating with said upper and lower tubes, open-ended conduits for a heating medium extending longitudinally 85 through the vertical water tubes with their end portions extending transversely through the upper and lower water tubes and communicating with the upper and lower portions of said chamber, and conduits for a heating medium disposed vertically in said water jacket with their upper and lower 90 ends communicating with upper and lower portions of said chamber.

3. A still comprising a hollow body defining a heating chamber and having an outlet neck leading from its upper end, a water jacket enclosing the sides and top of said body and a portion of said neck and provided with a steam outlet adjacent its upper end, upper and lower water conduits disposed horizontally in said chamber and spaced transversely from each other and having open ends secured in openings 95 formed in the walls of the heating chamber and communicating with said water jacket, vertical water conduits connecting the upper and lower horizontal conduits, and conduits for a heating medium extending longitudinally in the vertical conduits with their end portions passed through the upper and lower horizontal conduits and communicating 100 with the upper and lower portions of said chamber.

4. A still comprising a hollow body defining a heating chamber and having side walls and a tapered top terminating in an 105

outlet neck, a water jacket disposed about said body and having a tapered top enclosing a portion of the neck of the body and terminating in a neck disposed about the 5 neck of said body closed at its upper end and provided with a steam outlet leading from one side adjacent its closed upper end, water conduits extending through said heat-

ing chamber and communicating with said water jacket, and conduits for a heating medium extending through said water conduits and communicating with the upper and lower portions of said heating chamber.

In testimony whereof I affix my signature.

ERNON V. OLIVER. [L.s.]
